ARTHUR BATES, OF LEICESTER, AND HAROLD E. COOPER, OF NORWICH, ENGLAND,
ASSIGNORS TO UNITED SHOE MACHINERY COMPANY, OF PATERSON, NEW JER-
SEY, A CORPORATION OF NEW JERSEY.

TURN-SHOE RE-FORMING MACHINE.

1,121,967.

Specification of Letters Patent. Patented Dec. 22, 1914.

Application filed April 27, 1909. Serial No. 492,489.

To all whom it may concern:

Be it known that we, ARTHUR BATES and HAROLD E. COOPER, subjects of the King of England, residing at Leicester, in the county of Leicester, England, and Norwich, in the county of Norfolk, England, respectively, have invented certain Improvements in Turn-Shoe Re-Forming Machines, of which the following description, in connection with the accompanying drawings, is a specification, like reference characters on the drawings indicating like parts in the several figures.

This invention relates to improvements in machines for re-forming or otherwise operating on boots and shoes, and has particular reference to the manufacture of what are known in the art as "turn" shoes. A turn shoe is one in which the upper and the sole are sewn together with their wrong side outermost, the shoe subsequently being turned, to bring its right side outermost, either by hand or upon a machine. This operation of turning the shoe has the effect of distorting its shape considerably, so that it is customary, before any further operations are performed upon the shoe, to place the shoe upon a last and to beat and rub it with a hand tool to re-form it, *i. e.*, to re-turn it into its proper shape.

A special object of the present invention is to perform this re-forming operation in a better and more expeditious manner than has been possible heretofore and, accordingly, one feature of the invention is the provision of a machine for re-forming turn shoes comprising in combination means for stretching the boot and means which by molding the sole not only re-forms it, but stiffens it so that it can retain the boot in approximately the form into which it was stretched.

The means for stretching the upper may be an expandable jack of appropriate size and shape upon which the shoe is placed and which is then expanded, either by hand or power, to stretch the upper and cause it to conform to the shape of the jack. The jack may be expanded in a yielding manner to obviate danger of injury to the shoe.

In a construction wherein the jack is expanded and contracted mechanically a convenient arrangement comprises a clutch mechanism that automatically stops the con-

traction and expansion of the jack in either of its extreme positions to permit work to be removed from and placed upon the jack or to be operated upon while stretched.

The sole molding means may comprise any suitable beating-out device, such as a roller between which and the jack there is provision for relative motion so that the roller may act upon the sole of the shoe on the jack and rub it into shape. Preferably, the roller is rotated by connections from any suitable source of power and it may be provided with ribs or projections to effect a beating as well as a rubbing action upon the sole.

In a convenient construction the roller is movable by hand to act upon the work and there is a support for holding it in its inoperative position, any suitable driving connections being provided to convey motion to it from the machine of which it forms a part or from any other source of power. Conveniently, these connections can be arranged so that when the roller is placed upon its support it is automatically disconnected from the source of power, and conversely, when it is removed from the support into operation upon the work the connection with the source of power is established. Advantageously the connections may be flexible or may be made telescopic or otherwise variable in length so as to compensate for variations in the height of the sole upon the jack due to the "spring" of the shoe.

Another feature of the present invention is the provision of a machine for re-forming boots and shoes comprising in combination an expandable jack, a last support, a roller, and connections between the roller and its driver constructed and arranged to permit the roller while being driven to be brought at will into operative relationship either with the jack or with the last support.

It is obvious that this invention is applicable to other machines than machines for re-forming shoes and the several features of the invention, including those special ones before mentioned and others which have to do with the general utility of the machine, and also certain more important details of construction and combinations of parts, will appear more fully in connection with the following description of

the illustrated embodiment of the invention, reference being had to the accompanying drawings.

Figure 1 is a front elevation of the machine. Fig. 2 is a left side elevation. Fig. 2^a is a detail of Fig. 2. Fig. 3 is a vertical section on the line 3—3 of Fig. 1. Fig. 4 is a front elevation, partly in section, and on a larger scale showing connections for driving the beating-out device. Fig. 5 is a detail of Fig. 4, partly in vertical section at right angles to the plane of Fig. 4.

The frame 2 of the machine includes two columns 3 and 4, the former of which supports an expanding jack formed, as shown best in Fig. 2, of relatively movable arms carrying the fore part and heel portions of a shoe form. The fore part is shown as supported directly by the column 3, while the heel part is supported by a lever 5 which is fulcrumed at 6 to the column and extending downwardly into connection with means for actuating it to move the lever from and toward the fore part for distending lengthwise a shoe which may have been placed upon the jack or form when in its contracted position. This arrangement provides for thrusting the heel part of the form into the relatively substantial heel part of the shoe, thus drawing the forward portion of the shoe tightly about the fore part of the form or jack. The parts of the form are made removable to permit parts to be used which are of appropriate size and style for different shoes to be treated.

The lower end of the lever 5 is provided with an eye in which is held a cylindrical block. The block and the eye are bored transversely to receive a rod 8 which is screwed into a boss formed on an eccentric strap 10 which embraces an eccentric 12 on a shaft 14. The shaft is turned in bearings in the frame by a gear 15 meshing with a gear 16 having one-half the number of teeth that the gear 15 has and which is driven from the main driving shaft 18 of the machine. The lever 5 is yieldingly connected with the eccentric rod 8 so that the heel part of the jack will be thrust yieldingly when it is stretching the shoe and the rod, which is reduced where it extends through the lever, and has a shoulder at 20 through which it actuates the lever 5 positively in the direction for contracting the jack. A spring 22 encircles the rod 8 on the right hand side and the force for expanding the shoe is, therefore, transmitted through this spring to the lever. The tension of this spring is controlled by a hand wheel 24 threaded on the rod 8 and located in convenient position to be manipulated by the operator at any time to change the tension of the spring and thereby the force with which the shoe is being distended; for example, this hand wheel 65 may be manipulated while a shoe is held on

the jack in distended position and by such manipulation the force acting to distend the shoe may be manually increased or diminished after the automatic operation of the jack. The eccentric rod 8 also is provided with a hand wheel 25 by which it may be screwed more or less into the boss of the eccentric strap 10 to change the normal angular position of the lever 5 and therefore the normal relation of the lever and the fore part of the jack for shoes of different sizes. This provision renders unnecessary such frequent changes of the parts of the form or jack as would otherwise be required for different sizes of shoes.

The pinion 16 or the portion of shaft carrying it is connected to the main driving shaft 18 by a clutch which may be of any suitable form so arranged that when the pinion has made a predetermined number of revolutions said pinion will be automatically disconnected from the driving shaft. If the clutch is arranged to cause the pinion to stop at the end of one complete revolution the lever 5 will make one movement—as, for example, to expand the jack and distend the shoe—and then come to rest with the shoe in distended condition, and at the next actuation of the machine the lever will be reversely moved and come to rest with the jack in contracted position. If the clutch is arranged to give a plural number of rotations to the pinion 16 the lever 5 will repeatedly move the heel part of the form away from the fore part for rapidly expanding the jack and distending the shoe. The clutch will of course be arranged to cause the machine to come to rest with the shoe in distended condition. Each alternate actuation of the machine will preferably cause a single rotation of the pinion 16 to actuate the jack from an expanded to a contracted condition. A clutch controlling device 30 is shown in Fig. 2 arranged to be operated through a rod 32 depending from the hand lever 34 fulcrumed at 6 and which is normally held in the position shown by a spring 35. As has been earlier suggested, it is contemplated that the shoe which has been distended by the expanding jack substantially to its normal shape and size shall be treated to smooth and shape it so that it will have the desired appearance when removed from the jack. It is found that in making shoes of very light or very stretchy stock the upper is distended too much if the shoe is thus distended or otherwise treated while it remains on an expanding jack in which, as in the construction above described, the expansion is effected through a spring which continues to exert expanding force while the jack is at rest, as in Fig. 1. To prevent this difficulty in making such light or stretchy shoes the hand wheel 24, controlling the spring 22, may be adjusted to 130

relax the tension of that spring, or alternatively means may be provided for resisting the action of the spring while the shoe is held in distended condition and preventing further expansion of the jack. For this purpose an eccentric 36 is shown as mounted in the column 3 in front of the lever 5 and provided with an operating lever 38 by which it may be turned into position to limit the movement of the lever in the direction for expanding the jack. This eccentric may be positioned before the machine is started in the event that it is desired to use it as a stop for limiting the automatically effected expansion of the jack or the eccentric may be turned down to prevent further expansion of the jack and distention of the shoe while the shoe is being treated on the expanded jack. The operating lever 38 has a spring 39 plunger 39 for frictionally engaging a plate 40 to hold the lever in the position to which it has been adjusted. The rod 32 may have a lug 42 adapted, when the clutch controlling lever 34 is depressed for restarting the machine to contract the jack, to spring under the operating lever 38 and in the upward movement of said bar to turn the eccentric into an inoperative position. By this means the eccentric, after having been used to prevent further expansion of the jack during the treatment of a shoe may be restored to its inoperative position where it will not interfere with the normal expansion of the jack with the next shoe applied to it.

The driving shaft 18 is provided with fast and loose pulleys 45, 46, the former of which has an internal gear from which is rapidly driven a small pinion on a shaft 48 connected by beveled gears 49 with a vertical shaft 50, see Figs. 1 and 3. The upper portion of the shaft 50 is tubular and telescopes a depending shaft 52 having a toothed collar 54 adapted for engagement with a recessed collar 55 on the shaft 50 for clutching the two shafts together. The shaft 52 is connected by a ball and socket or other suitable joint with the lower one of two telescopic sections 56, 57 of an extensible shaft, which in turn is connected, as shown in Figs. 4 and 5, by a universal joint with a shaft 58 mounted in a frame 60 and connected by beveled gears with a shaft 62 upon which is fast a beating-out roll or other suitable tool 64. The frame 60 or extensions of the shaft 62 carried therein are provided with handles 65 by which the roll may be lifted and moved over the work while it is being rotated through the connections described with the driving mechanism. The machine is provided with a bracket 70 conveniently arranged to receive the roll when the roll is not to be used. The bracket is so located that in placing the roll in it the extensible shaft 56, 57 is drawn out and the collar 54 is lifted to withdraw its projections from the recesses in the collar 55 and thereby disconnect the shafts 50 and 52 so that the shaft 52 is not rotated by the shaft 50. When the roll is lifted from its supporting bracket and brought into position for operating upon the shoe the distance between it and the frame of the machine is shortened sufficiently to allow the clutch members 54, 55 to engage and thereby cause the roll to be driven while it is in position to treat the shoe. A spring is arranged between the members 56, 57 of the extensible shaft to allow variations in the working position of the roll as it is moved over different portions of the shoe. The driving connection between the shaft 52 and the shaft 56 may conveniently comprise a ball formed in the lower end of shaft 56 and held in the socket in the other shaft, said ball being provided with a transverse bar or laterally projecting studs 72 capable of vertical movement in slots in the socket walls. The driving connection between the shaft section 57 and the section 58 is similarly formed by a ball having a transverse bar 73 and the frame 60 has depending flanges 74. This connection permits, within certain limits, a free tipping movement of the roll in all directions. These tipping connections allow the roll to be tilted as well as moved forwardly and backwardly for rubbing or beating down different portions of the shoe to be treated. They also permit a lateral movement of the tool to bring it into position to operate upon a shoe carried by a shoe support on the second or right-hand column 4. It is found desirable sometimes to remove a shoe from the expandable jack after the shoe has been stretched and to apply it to a non-expandable last or support such as that shown on the right-hand column. The shoe is then beaten out by the use of the roll 64.

In the use of the machine the shoe is applied to a jack when the latter is contracted—that is, when the heel part is positioned closely adjacent to the fore part by the engagement of the shoulder 20 on the eccentric rod with the cooperating portion of the lever 5. At this time the gear 16 will be disconnected from the driving mechanism and the beating roll 64 will rest in its bracket 70, as shown in Fig. 1, with the clutch members 54, 55 disconnected. The shoe will have been turned right side out before being applied to the expandable jack and to start the machine the operator will depress the controlling lever 34, whereby the eccentric will be actuated to rock the lever 5 yieldingly through the spring 22 as many times as the clutch is arranged for and will come to rest with the jack in the position shown in Fig. 2 in which it holds the shoe in distended condition. The rubbing roll or beating device is then lifted

from its support and while being moved into operative relation to the shoe, it becomes automatically connected with its driving mechanism by the descent of the 5 clutch member 54 into driving engagement with the clutch member 55, whereby the roll is rapidly turned. The operator carrying the roll in his two hands moves it over the shoe into such positions and with such pressure as in his judgment is required for 10 beating-out the shoe. This operation upon the shoe sole reforms it or shapes it and stiffens the sole so that the sole assists substantially in maintaining the relatively 15 flexible shoe upper in its distended or reformed condition after the shoe has been removed from the jack. To restart the machine for contracting the jack the operator again depresses the controlling lever 34 and 20 the machine comes to rest with the heel piece rocked toward the fore part of the divided last or form so that the shoe can be readily stripped off the jack without distorting its shape. The shoe may then be 25 permitted to dry on a rack for making permanent the shape given to it on the jack.

If the shoe under treatment at any time is being stretched too much or too little the tension of the spring 22 will be adjusted 30 by the hand wheel 24 and if it is desired to prevent the shoe from being distended more by the tension of the spring 22 during the beating-out operation on the shoe sole, the eccentric 36 may be positioned as shown in 35 Fig. 2* to lock the lever 5 against further movement or the eccentric may be used to move the lever in opposition to the spring 22 to contract and then reexpand the jack. The heel piece of the jack is preferably 40 provided with a sole plate which extends forwardly to bridge the space between the heel piece and the fore part whereby the expanded jack presents a continuous sole portion to sustain the sole of the shoe for the operation of the beating-out device thereon. The 45 front portion of the plate is thin and beveled so that there is no abrupt shoulder at its end. The plate is preferably of resilient material and so positioned and secured 50 upon the heel piece that it will in all positions of the latter hug the bottom face of the fore part.

Having explained the nature of this invention and described a machine embodying the same and particularly adapted for re-forming turn shoes, although it will be understood that the invention may be used for any other purposes for which it is adapted, we claim as new and desire to secure by Letters Patent of the United States:

1. A machine for operating on shoes, having in combination, an expandible jack, power-driven means operating through a 65 yielding element to expand the jack to dis-

tend the shoe on the jack, and means to be held in the hands of and manipulated by the operator over the shoe bottom and to be connected with or disconnected from said power driven means separately from the 70 jack for operating on the shoe while it is in distended condition.

2. A machine for re-forming turn shoes, having in combination, means for distending the shoe to substantially its normal 75 shape and size after it has been turned and holding it in its distended condition, a manually guided beating-out tool to operate on the sole while the shoe is so held and power driving means having operative connection with said means to distend the shoe, and with said tool to beat out the shoe.

3. A machine for re-forming turn shoes, having in combination, an expandible jack, power-driven means yieldingly connected 85 with the jack to expand it, a beating-out tool and tool driving connections arranged to permit the tool to be started and stopped while the shoe is maintained in distended condition upon the jack.

4. A machine for re-forming turn shoes, having in combination, an expandible jack, power-driven means to expand the jack and automatically come to rest holding the jack and the shoe thereon in expanded condition, a manually sustained and manipulated shoe sole beating-out device, and power-driven means for actuating said device to beat out the shoe while it is held in expanded condition, said machine having provision for controlling the operation of the beating-out device separately from the jack.

5. A machine for re-forming turn shoes, having in combination, an expandible jack, power-driven means to expand the jack and automatically come to rest holding the jack and the shoe thereon in expanded condition, a beating-out device movable from an inoperative position at the will of the operator, a driven member, and means operative 105 on a movement of said beating-out device from inoperative position to operative position to establish driving connection between said device and said driven member.

6. A machine for re-forming turn shoes, having in combination, an expandible jack, power-driven means to expand the jack and automatically come to rest holding the jack and the shoe thereon in expanded condition, a beating-out device constructed and arranged to be carried by the hands of the operator from an inoperative position to an operative position, a driven member, and means adapted for establishing and discontinuing connection between the driven member 115 and the beating out device while said device is being carried toward and from operative position.

7. A machine for re-forming turn shoes, having in combination, an expandible jack 120

- adapted to receive a shoe, power-driven mechanism arranged to expand the jack while it remains in shoe receiving position, a manually controlled and manipulated shoe sole beating-out roll, power-driven mechanism for said roll, and means which can be operatively connected at will with said last named power-driven mechanism for actuating the roll to do its work while the shoe is held in distended condition by the jack.
8. A machine for re-forming turn shoes having, in combination, an expansible jack to distend the upper of a shoe, power driving means for effecting expansion of the jack and operative subsequently to effect contraction thereof, a beating-out device arranged for manual manipulation to rub and thereby extend the sole of the shoe and power driving means operatively connected with said beating-out device.
9. A machine for re-forming turn shoes, having in combination, an expansible jack to distend the upper of a shoe, a beating-out device serving to distend the sole, power-driven means to actuate the jack, and power driving means operatively connected with said beating-out device to actuate the beating-out device for the purpose described.
10. A machine for re-forming turn shoes, having in combination, an expansible jack to distend the upper of a shoe, a beating-out device serving to distend the sole, power-driven means to expand the jack, and independently controlled power-driven means for actuating the beating-out device.
11. A machine for re-forming turn shoes, having in combination, an expansible jack to distend the upper of the shoe, a beating-out device, a spring, means to put the spring under tension tending to expand the jack and stretch the upper, and means to actuate the beating-out device to stretch the sole to facilitate and compensate for the stretching of the upper.
12. A machine for re-forming turn shoes, having in combination with suitable power driving mechanism, a jack to support a shoe, a shoe sole beating-out device movable from an inoperative position to a position for operation upon the bottom of a shoe sustained on said jack, power driving mechanism for said beating-out device and means adapted to establish driving connection between said device and the driving mechanism as the device is moved from its inoperative position.
13. A machine for re-forming turn shoes having, in combination with suitable driving mechanism, a jack to support a shoe, a shoe sole beating-out device movable from an inoperative position to an operative position over the shoe bottom, a continuous physical connection of said device with said driving mechanism, and means comprising relatively movable elements in said physical connection for establishing a mechanical driving connection between said device and said mechanism as an incident to movement of said device toward the shoe and breaking such connection as an incident to movement of said device from the shoe for starting and stopping rotation of said device.
14. A machine for re-forming turn shoes having, in combination with suitable driving mechanism, a jack to support a shoe, a shoe sole beating-out device movable relatively to said driving mechanism from an inoperative position to a position over the shoe bottom, and means operated entirely by said relative movement of the beating-out device to its driving mechanism to establish mechanically a driving connection between said device and the driving mechanism during movement of said device from said inoperative position to said position over the shoe bottom.
15. A machine for re-forming turn shoes having, in combination with suitable driving mechanism, a jack to support a shoe, a beating-out device adapted to be manually guided over the work, a support to hold said device when it is not in use, and means to establish mechanically a driving connection between said device and said driving mechanism as a necessary incident to movement of the device from said support to work engaging position.
16. A machine for re-forming turn shoes having, in combination with suitable driving mechanism, a jack to support a shoe, a shoe sole beating-out device manually movable from an inoperative position to an operative position over the bottom of a shoe supported on the jack and movable over the shoe bottom to treat different parts of the sole, and a driving connection between said device and said mechanism including a clutch controlled entirely mechanically as an incident to movement of said device.
17. A machine for re-forming turn shoes having, in combination with suitable driving mechanism, a jack to support a shoe, a beating-out device movable from and toward the shoe and rotatable in engagement with the shoe to do its work, a continuous physical connection of said device with said driving mechanism, and means comprising relatively movable elements in said physical connection for establishing a mechanical driving connection between said device and said mechanism as an incident to movement of said device toward the shoe and breaking such connection as an incident to movement of said device from the shoe for starting and stopping rotation of said device.
18. A machine for re-forming turn shoes, having in combination with driving mechanism, a jack to support the shoe, a beating-out roll to treat the sole, a bracket for the roll at a higher level than the sole of the

shoe, an extensible connection from the roll to the driving mechanism, and a clutch arranged to be opened when the roll is raised to the bracket and closed when the roll is lowered to the work.

19. A machine for re-forming turn shoes, having in combination with driving mechanism, a jack to support the shoe, a beating-out roll to treat the sole, a bracket for the roll at a higher level than the sole of the shoe, and an extensible connection from the roll to the driving mechanism arranged to cause the roll to be stopped when it is raised to the bracket and to permit the vertical movements of the roll required for its several working positions without interrupting the driving connection.

20. A machine for re-forming turn shoes, having in combination an extensible jack, to support a last, a beating-out roll, suitable driving mechanism, and connections between the driving mechanism and the beating-out roll constructed and arranged to permit the roll while being driven to be brought at will into operative relationship either with the jack or with the shoe on the jack.

21. A turn shoe reforming machine having, in combination, means affording an uninterrupted support for the sole of the shoe throughout the length of the shoe and acting

expansively upon the shoe sole and upper in a yielding manner throughout the reforming operation, and a mechanically operated hand guided roller for beating out the supported sole throughout its length progressively and which by its action on the sole, contributes to the shoe expanding action of the first mentioned means.

22. An apparatus of the class described having, in combination, a jack to support a shoe in position to be treated, a tool for treating the shoe constructed and arranged to be held in and manipulated by the hands of the operator, a holder to receive the tool when it is not in use, and driving means for the tool including a clutch which can be moved with the tool in the hands of the operator, said apparatus being provided with means operating positively to cause opening of the clutch to be effected by the return of the tool to the holder.

In testimony whereof we have signed our names to this specification in the presence of two subscribing witnesses.

Corrections in Letters Patent No. 1,121,967.

It is hereby certified that in Letters Patent No. 1,121,967, granted December 22, 1914, upon the application of Arthur Bates, of Leicester, and Harold E. Cooper, of Norwich, England, for an improvement in "Turn-Shoe Re-Forming Machines," errors appear in the printed specification requiring correction as follows: Page 5, line 55, for the word "the" read *its*; page 6, line 19, after the word "jack" strike out the comma; same page, line 20, for the word "last" read *shoe*; and that the said Letters Patent should be read with these corrections therein that the same may conform to the record of the case in the Patent Office.

Signed and sealed this 15th day of June, A. D., 1915.

[SEAL.]

J. T. NEWTON,

Acting Commissioner of Patents.
